TABULATOR

Einar Lawrence Kirkegaard, Detroit, Mich., assignor, by mesne assignments, to International Business Machines Corporation, New York, N. Y., a corporation of New York

Application June 27, 1930, Serial No. 464,191

5 Claims. (Cl. 235—92)

The invention concerns mechanism designed to extend the utility of mechanical accounting systems of the perforated card type and has for its principal object the provision of devices facilitating the use of perforated cards as ledgers in businesses which have large numbers of small accounts.

An equally important object is the provision of such mechanism which permits statements, bills or invoices to be prepared directly from such perforated ledger cards by the use of well known types of tabulating machines thus obviating the necessity for clerical work in the preparation of such statements.

15 The invention, while adapted to various uses, will be illustrated and described in connection with the accounting system of a public utility corporation supplying services in connection with electricity, light, power, gas and the like. It is 20 customary to install meters on the premises of users of electricity and gas on which the consumption of these commodities is registered. An employee of the corporation makes periodic visits to read the meters, entering the readings in a 25 meter read book which forms the book of original entry. This book shows the last previous and present readings of the meters and the difference between the two, representing the consumption of the commodity during the selected 30 period. According to the present invention it is proposed to form perforated ledger cards from these books of original entry. The ledger cards are punched in differential locations, in the well known manner, to represent different data and 35 ordinarily a single card is prepared for the consumption of several commodities by each consumer during the accounting period. Thus each ledger card is punched with identifying data of the consumer, identifying data of the particular 40 commodities, present and previous readings of the meters, the differences between the readings, representing consumption during the period, and the amount due for this consumption in each commodity.

45 This punched card constitutes the sole ledger and obviously presents all the advantages for auditing and statistical purposes which usually result from these mechanical accounting systems.

The statements, bills or invoices which are 50 sent out to consumers at the end of the accounting period may be prepared directly from the perforated ledger card. Each consumer may have a single card for gas and electricity consumption. In order to save postage it is proposed 55 according to the present invention to prepare the

bills on post cards although, of course, the system is not to be limited to this manner of operation. Suitable feeding mechanism is provided to feed the post cards to the printing mechanism of the tabulator while the perforated ledger cards are fed through the accounting section. The tabulator is provided with mechanism to accumulate data from successive cards and cause a total to be taken of the items in the particular classification group.

10 The post cards are fed to the platen of the tabulating machine by special feeding mechanism and the present reading, previous reading, consumption and amount due for the consumption are printed on the post card from the perforated ledger card for one of the commodities. Incidentally the amount due is entered into an 15 accumulator and at the end of the billing operation the total of the amount due for the particular consumer is also printed on the post card. The line spacing for the several items on each 20 post card is obtained from the usual line spacing mechanism of the machine. After the total for the card has been printed, the special feeding mechanism feeds the printed post card out of the 25 machine and feeds a blank post card into printing position to receive printed data from the following card. Thus the consumer's itemized bills are obtained in convenient form directly from the ledger without any clerical or copying 30 work.

The particular method of handling the ledger cards may vary. Ordinarily after the statements or bills are made and mailed the ledger cards are placed in a special container and as each bill is 35 paid its particular ledger card is withdrawn from the special container and placed in the permanent file. At the end of a certain period of time all the ledger cards remaining in the special container which now represent overdue accounts are 40 again run through the tabulator and special follow up notices are printed from them in the same manner as the original bills were printed. These ledger cards are then replaced in the special container and removed as before when the bills are 45 paid. At the end of another period of time the ledger cards still remaining in the container may be again run through the tabulator to print special shut-off notices.

Another form of accounting might be employed 50 in which the original bill, follow up and shut-off notices would be printed in one operation on the original passing of the ledger cards through the tabulating machine. The number of follow up and shut off notices which are actually needed is 55

small, however, and the former method is preferred.

The invention will now be explained more explicitly in connection with the accompanying drawings in which:

Fig. 1 shows a post card with a severable stub arranged as a bill and having amounts and totals from certain perforations of the card shown in Fig. 2.

Fig. 2 shows a tabulating card punched to form a ledger according to the invention.

Fig. 3 is a section through the notice card feeding mechanism of the tabulator.

Fig. 4 is an outside view of the driving mechanism of the notice card feeding devices.

Figs. 5 and 5a taken together form a circuit diagram of a complete tabulator on which bills or statements may be prepared according to the invention.

Referring to Fig. 2 a ledger card is shown which is punched to represent all the data pertaining to the consumption of gas and electricity for a certain consumer during an accounting period. This card is of well known form and carries indicia arranged in columns to represent the numerals from 0 to 9. The card is divided into two sections one for each class of service; in the present case gas and electric service. The present and prior meter readings for each are punched in appropriate columns as shown, followed by the differences which represent the consumption during the period. This data is all taken from the meter read book. The columns headed "Amount" are punched to represent the amount due for the consumption shown in the adjacent columns and the last columns to the right are punched with a number identifying the consumer.

By mechanism which will be hereinafter described a blank bill is first fed to the platen of the tabulating machine so that its first printing impression from a particular consumer's card will occur along the first printing line as shown in Fig. 1 whereon all data pertinent to one class of service is recorded together with the consumer's account number. On the line following will be printed all data relating to a second class of service. A total is also printed which is the sum of the amounts due for each class of service. Preferably the post card is scored or perforated into readily detachable portions of which one part may constitute the consumer's receipt, another the collector's check, and a third the cashier's stub. The amounts due and their totals appear on two portions of the bill and hence this series of items and totals must be printed from the same columns of the ledger tabulating card from two different sets of type as will be hereinafter disclosed.

The ledger cards are fed through a tabulator of well known type which is fully illustrated and described in the patent to Daly and Page, No. 1,762,145, issued June 10, 1930.

The machine is provided with the usual card feed devices and accumulating sections shown diagrammatically in the wiring diagram of Figs. 5 and 5a and a printing section illustrated in Figs. 3 and 4 which is provided with special feeding mechanism for feeding the bills. The printing section contains type bars coordinated to the counters so that the several amounts entered into the counters and the totals thereof may be printed. In the present example those columns of the ledger cards which contain perforations representing present reading, prior reading, consumption and amount are each connected with an ac-

cumulator or counter so that the data may be printed from the associated printing bars.

Under control of the card in Fig. 2, the machine is adapted to list directly upon the bill information concerning gas service on the first line 5 of the bill in Fig. 1. Concurrently, information concerning electric service is entered into appropriate counters to be stored until the bill has been spaced to the next printing line whereupon such data is read from the counters and printed on the 10 second line of the bill.

The information in the fields headed "Amount" is entered into the same counter for both the gas and electric service during the card feeding cycles of the machine and the sum 15 thereof printed concurrently with the printing of the second line of data from the storage counters. The machine is adapted to automatically present a blank bill for each card fed through the machine as long as cards continue to be advanced 20 from the hopper.

The general arrangement of the post card or bill feeding mechanism is most clearly illustrated in Fig. 3. The platen of the tabulator is shown at 10 and opposite it, arranged for vertical 25 movement are the type bars 11 each of which carries a type head with ten type 12 representing the digits from 0 to 9. A rock shaft 13 rocks first clockwise and then counterclockwise during each printing cycle, both listing and totaling, to 30 first raise the different type 12 successively to printing position opposite the platen and then lower the type bars to home position.

The perforated ledger cards are fed through the card feeding section synchronously with the 35 movement of the type bars and suitable analyzing mechanism causes differentially timed electric impulses according to the location of the perforations in the several card columns. These impulses control electromagnetic devices to arrest the upward movement of the type bars so that the type 12 corresponding to the perforations are stopped in printing position and at a certain time hammers 14 are tripped to force the selected type against the platen 10 and cause 40 printing. This is the listing operation. The total printing operation is entirely similar except that the differentially timed impulses which arrest the type bars originate from devices which feel out the position of the counter wheels and 45 time the impulses according to the accumulated amounts standing on the counters. These operations are well known and fully described in the above mentioned patent and need no further explanation.

The bill post cards 15 (Fig. 3) are placed in a suitable hopper 16 from which they are fed one by one by means of a reciprocating picker 17 operating on the lowermost card of the stack. The picker 17 operates on a total taking and reset operation and feeds the lowermost card into the bite of rolls 18. On a reset and total taking operation the rolls 18 feed the card into the bite of a second set of feed rolls 19. The rolls 19 also operate during reset and feed the card to the 65 platen 10, in position to receive the first line of printing. After the operation is once started each reset and total taking operation feeds a fresh card to the platen. The platen in addition to its usual line spacing movement is given an 70 extra movement on total taking and reset so that after the total is printed the card is fed into constantly running reject rolls 20 and 21 which deliver it to a discharge receptacle 22. These operations and the mechanism for effect- 75

ing them will be described in detail hereinafter but first the usual line spacing devices for moving the platen during listing will be briefly explained.

5 The rock shaft 13 (Fig. 3) rocks clockwise during each listing cycle and an arm 23 fixed thereto carries a pin 24 which rocks a frame 25 counterclockwise about its pivot 26. A link 27 pivoted to frame 25 is thereby lowered. The 10 lever has connection with the usual spring pressed pawl which cooperates with a ratchet wheel fixed to the platen shaft and thereby feeds the platen one line space after each listing printing operation. This mechanism as usual 15 serves to space the post card bills one line space after each item is printed on them.

The special feeding mechanism which operates after total printing to feed the printed bill free of the platen and to feed a fresh card bill to the 20 platen is detailed in Figs. 3 and 4. In Fig. 4 the total print shaft which makes one revolution on each total printing and reset operation is shown at 30. During the first half of its revolution total printing is effected and during the last half of 25 its revolution the counters are reset to zero. The picker and the several special feed rolls are operated from this shaft during the last half of its revolution so that the special bill feeding operation occurs after total printing. A disk 31 is 30 fixed to shaft 30 to operate a pitman 32 of adjustable length. The pitman reciprocates a rack 33 guided in a grooved block 34. The rack meshes with a gear 35 to which is fixed an arm carrying a pivoted pawl 36. This arrangement, 35 on rotation of the total print shaft 30, causes gear 35 to rotate substantially one third of a revolution in a counterclockwise direction and then one third of a revolution in a clockwise direction. Free on shaft 37 is a gear 38 having 40 three times as many teeth as the gear 35 and fixed to the gear is a disk 39 provided with three evenly spaced notches to cooperate with pawl 36. The gear 38 drives a gear train with a three to one ratio which reciprocates the picker 17 45 through links 40, one on each side of the structure, and drives the platen 10 through a chain and sprocket connection 41. The sprocket connection to the platen 10 includes a one way clutch designated generally at 10a, so that the 50 platen may be line spaced by the usual line spacing mechanism without interference from this special drive.

The lower rolls 18 are mounted on the shaft 42 which carries the eccentrics for picker operating links 40 and the rolls 19 are driven from a chain and sprocket geared to this same shaft. The constantly running reject rolls are driven by a special motor 43 through a belt and pulley arrangement shown at 44. The driving shafts of 60 reject rolls 20 and 21 are shown at 45 and 46 respectively.

The operation and coordination of these mechanisms will be briefly explained in connection with Fig. 3. Assuming that a stack of post cards 65 have just been placed in the hopper 16 it is first necessary to effect three reset operations of the tabulator to bring the lowermost one of the stack into its first printing position on the platen. The first reset operation on rotation of shaft 70 30 first moves rack 33 upward to the right and rotates gear 35 counterclockwise to bring pawl 36 into cooperation with one of the notches in disk 39. Then as the rack moves downward to the left gear 35 rotates clockwise and pawl 36 75 rotates disk 39 and attached gear 38 a third of

a revolution. Owing to the three to one gear ratio this causes picker 17 to make one complete reciprocation and special feed rolls 18 and 19 to make one revolution. The picker 17 therefore feeds the lowermost card bill into the bite of 5 rolls 18. On the next reset operation rolls 18 feed this first bill to the bite of rolls 19 and the picker 17 feeds the next bill to rolls 18. On the third reset operation the first card bill is fed into printing position on the platen due to the further 10 operation of the mechanism as explained above. After this the several items may be printed on 15 the bill from the tabulating ledger cards. After each item the platen is stepped one line space by the usual line spacing mechanism. This line 20 spacing has no effect on the special bill feeding device owing to the presence of the one way clutch in the latter. After the first customer's tabulating card is itemized and totaled the reset operation causes the special feeding mechanism to 25 again function whereby the movement of the platen feeds the printed bill to the constantly running reject rolls 20 and 21 which deposit it in the discharge container 22. Incidentally a blank post card bill is fed to the platen. 25

The operation of the complete machine so that the previously described printing and adding operations may be accomplished will now be explained in connection with Figs. 5 and 5a which show a simplified but substantially complete circuit diagram of the tabulator disclosed in the patent previously mentioned. During adding and listing operations the tabulator is driven by the tabulating motor TM which is controlled by a group of circuits and relays in the upper right 30 hand portion of the drawings. During totaling and reset operations the tabulator is driven by reset motor RM controlled through associated circuits and contacts. Both of these motors are so arranged that the machine performs complete 35 cycles after they are once started. In order that the counters of the machine may be cleared of previous data for starting a tabulating run, the circuits are arranged so that a reset cycle must precede the first adding cycle. As previously explained, three reset cycles are necessary to get the first bill post card onto the platen. To simplify the explanation, it may be assumed that automatic reset switch 50 is open at this time. The three reset cycles may be obtained by depressing 40 the reset key R three separate times, waiting each time until the reset operation is complete. The closure of the contacts of reset key R establishes a circuit through the reset motor in series with the total clutch magnet T which controls a one revolution clutch serving to clutch the total print and 45 reset mechanisms to the drive shaft of the motor. Immediately after starting, a cam contact P-1 closes, shortcircuiting the initial circuit for the total or reset clutch magnet T. Toward the end 50 of the cycle the cam contacts P-1 open and stop the reset motor at the end of a single reset operation. After three such operations, the first post card has been fed to the platen in position to 55 receive its first line of printing. 60

It is now necessary to start the tabulating ledger cards through the machine. It may be assumed for the sake of simplicity that the automatic start switch 51 is open and the start key is depressed, closing contacts ST. Closure of contacts ST 65 causes operation of motor TM and feeding of cards to commence. The circuit established includes a normally closed relay contact 53 controlled by its coil 52. Energization of coil 52 will open contacts 53 to interrupt card feeding oper- 70

ations and upon such interruption, if reset switch 50 is closed, the machine will automatically perform a total printing or reset operation. In a manner to be described the coil 52 will be controlled to cause the machine to alternately execute a card feeding cycle and a totaling printing cycle for each card.

During the card feeding cycle, the first line of information is printed upon the bill, being read directly from the card by the lower brushes. During the total printing cycle, the second line of information is printed upon the bill; this data being printed under control of counters into which such data had previously been entered while the card passed the upper brushes. The information in the column headed "Amount" of the "gas" portion of the card is entered into a counter during passage of the card by the upper brushes and the information in the column headed "Amount" of the "electric" field of the card is entered into the same counter while the card is passing the lower brushes thus giving an accumulation of these two amounts which is printed during the total printing cycle together with the other data printed on the second line of the bill.

Referring to Fig. 5, a cam contact LP-7 is adapted to close momentarily near the end of a total printing or reset cycle to set up the relay contacts 56, 57 through the following circuit: from line 60, contact LP-7, coil 55, contact T4, closed at this time, back to line 61.

The coil 55 is adapted to shift its related contacts 56, 57. The closure of contact 56 establishes a holding circuit from line 60 through coil 55 and contact T4. The concurrent opening of contact 57 will deenergize coil 52 permitting its related contact 53 to close so that if the machine is set for automatic restarting, card feeding commences following the completion of the reset cycle. During the card feed cycle cam contact T4 will open to deenergize coil 55; contact 57 will again close and contacts 53 will be opened. If the switch 50 is closed, a total printing cycle ensues, followed by a card feeding cycle as explained above. In this manner the machine is adapted to go through a card feed cycle, then a reset cycle, card feed cycle and so on.

A card lever relay contact 54 is provided in parallel circuit with contact T4 and is adapted to be open as long as cards feed past the upper brushes. During such continuous feeding of cards the usual card feed lever contact UCL is closed and thereby maintains the coil UCL3 which is in series therewith energized. Coil UCL3 when energized, opens contact 54. Thus, upon failure of cards to feed contact 54 will close and prevent the automatic shifting of contacts 56, 57. A switch S is also provided which when closed, shunts out contacts 54 and T4 and maintains coil 55 constantly energized. This will permit the machine to perform ordinary tabulating and listing operations independently of the aforesaid controlling circuits.

The manner in which the information to be printed on the bill is obtained from the card will now be explained. In Figs. 5 and 5a, the various banks of printing elements are numbered 1a, 2a, 3a, etc. These banks include printing magnets 70 which when energized interrupt the type bar 70 11 of Fig. 3 in position to print.

The several accumulators are numbered 1, 2, 3, 4, 5. These units include the usual adding magnets 71 and the usual total printing contacts 72 which are adapted to close differentially in accordance with the amount contained in the

accumulator. These parts are shown diagrammatically herein but their exact mechanical arrangement is well known and is fully shown and described in Patent No. 1,379,268 granted to C. D. Lake, May 24, 1921.

The lower brushes are labelled LB and the upper brushes UB. The brushes LB which read the present and prior meter readings, consumption, account number and symbol G relating to gas in Fig. 2, are plugged as shown in Fig. 5, by wires 73 to printing banks 1a and 2a and such other printing banks as desired to obtain the duplicate printing as in Fig. 1. The brushes LB which read the present and prior meter readings, consumption and symbol E relating to electric service, are plugged by wires 74 to accumulators 1 and 2 where this information is stored. Following such entry and the printing of the gas items the machine goes through a total printing cycle as already explained during which the "electric" information is transferred through contacts 72 and plug wires 75 to the appropriate columns of the printing banks. Each column of printing elements includes a double contact 76 adapted to be shifted by magnets 77 during total printing operations to connect the magnets 70 to plug wires 75. The time of energization of magnets 77 is controlled by cam contacts LP6, LP8, LP9, and LP10 operated by the total printing mechanism.

The "amount" of gas service and the "amount" of electric service may be similarly plugged for printing in selected columns, the gas amount being printed directly from the card while the electric amount is first set up in a counter and read therefrom in the following total printing cycle.

In order to complete the bill in a minimum number of cycles of operation, a switching arrangement is provided between two counters so they reset in alternate cycles and also control total printing in alternate cycles. In Fig. 5a are shown cam contacts S1 and S2 which turn during card feeding cycles at half the machine speed; that is they make one revolution for two turns of the card feeding mechanism. 80 and 81 are the usual zero button magnets and function when energized to prepare their respective counters 4 and 5 for total printing and resetting. The time of operation is such that counter 4 is reset during one total printing cycle and counter 5 is reset during the next total printing cycle. Magnets 80 and 81 are shown diagrammatically in the circuit diagram and their mechanical association with the counter is fully shown and described in Patent No. 1,775,132 granted to C. D. Lake et al, September 9, 1930.

The upper brushes UB associated with the gas "amount" field are connected by plug wires 78 to counter 4 through switching contacts 82 so that the gas amount is added in this counter.

Similarly plug wires 79 connect the lower brushes LB associated with the electric amount to magnets 71 of counter 5 through other contacts 82. After the gas amount has been entered in counter 4 and before the next adding or card feeding cycle commences, contact S2 will close and energize magnets 83 to shift the various contacts 82 so that when the card under consideration passes the lower brushes LB the "electric" amount will pass from the brushes to the lowest blades of the contacts 82 associated with counter 5 to the magnets 71 of counter 4 thus adding this amount to the gas amount already therein.

Concurrently with this operation, the gas amount of the next succeeding card is being

sensed by the upper brushes and passed through the lowest blades of the contacts 82 associated with counter 4 to be entered in counter 5, where such amount remains during the ensuing total printing cycle since this counter will not reset at this time since lower contacts S1 are open during this cycle preventing the energization of magnet 81. However, since upper contacts S1 are closed, energizing magnet 80 which closes contacts 80a and also conditions counter 4 for resetting, the total printing contacts 72 of counter 4 will now function to cause total printing in bank 6a, being connected thereto by plug wires 75 after which counter 4 is reset in preparation to receive a new 15 "gas" amount while counter 5 is receiving an "electric" amount.

Where a card is perforated with information concerning only one type of service or commodity the operation of the machine is the same as described above. If the "electric" service field of the card is unperforated, no printing will be effected on the second line of the bill except a total which will be a repetition of the "gas" amount. In like manner, if the "gas" service field is unperforated, nothing but "account number" will be printed on the first line of the bill. Electric service items and total which is a duplication of electric amount will be printed on the second line of the bill. The printing of the symbol G or E will then denote the classification of service being billed, the G being listed directly from the card and the E being printed as a result of a "one" which is set up in a storage counter in any selected column. The type bars which these symbols control will, of course, have these characters substituted for the numerals corresponding to the index point position used on the card.

What is claimed is as follows:—

1. In a machine of the class described, the combination of a single accumulator, a plurality of analyzing stations, each one designed for analyzing a different one of a plurality of card fields of the same perforated record, means for moving the record past said stations in succession, and means for successively connecting the sta-

tions related to the different card fields with the accumulator as the plurality of fields pass the related analyzing stations.

2. In an accounting machine, a plurality of record analyzing stations, means for moving records past said stations in succession, a plurality of entry receiving devices, each of which is adapted to receive entries under control of said analyzing stations, and means for connecting each analyzing station in turn with each of said entry receiving devices whereby each entry receiving device will receive a succession of entries from the analyzing stations.

3. In a machine of the class described, a plurality of record card sensing stations, means for moving a record card past said stations in succession, an entry receiving device, and means including automatically operable switching mechanism for causing said device to be controlled by each of said stations in succession as the record 15 card moves past the same.

4. In a record controlled accounting machine, a plurality of record analyzing stations for reading perforated record cards, means for moving a card past each of said stations in succession, an 25 accumulator and means including automatically operable switching mechanism for causing said analyzing stations to progressively enter into said accumulator amounts sensed successively by said analyzing stations on a single record card as it is moved past the same, said switching mechanism operating to prevent control of said accumulator by one station while another is controlling entering of an amount.

5. In a machine of the class described, the combination of a single accumulator, a plurality of brush sensing stations each one designed for sensing a different one of a plurality of card fields of the same perforated record, means for moving the record past the said sensing stations 40 in succession and means including electrically controlled switching devices for successively connecting the sensing stations related to the different card fields with the accumulator as the plurality of fields pass the related sensing stations. 45
